US0D1073073S

(12) **United States Design Patent** (10) **Patent No.:** **US D1,073,073 S**
(45) **Date of Patent:** **** Apr. 29, 2025**

(54) **MEDICAL DEVICE**

(71) Applicant: **Stryker Corporation**, Kalamazoo, MI (US)

(72) Inventors: **Neil G. McIlvaine**, Seattle, WA (US); **Christopher G. Alviar**, Seattle, WA (US); **Jeremy Edward Brummett**, Redmond, WA (US); **Cathlene Buchanan**, Shoreline, WA (US); **Jonas Buck**, Berlin (DE); **Kenneth Howard Dickenson**, Bellevue, WA (US); **Jeffery Scott Edwards**, Bellingham, WA (US); **Kenneth J. Peterson**, Shelton, WA (US); **Johanna Schoemaker**, Berlin (DE); **Mitchell A. Smith**, Sammamish, WA (US); **Fernd van Engelen**, Bothell, WA (US); **Markus Wierzoch**, Carmel, IN (US)

(73) Assignee: **Stryker Corporation**, Portage, MI (US)

(**) Term: **15 Years**

(21) Appl. No.: **29/844,120**

(22) Filed: **Jun. 27, 2022**

CLAIM

The ornamental design for a medical device, as shown and described.

DESCRIPTION

FIG. 1 is a top, front, right-side perspective view of a medical device;

FIG. 2 is a bottom, back, left-side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The dashed broken lines depict portions of the medical device that form no part of the claimed design. The dot-dashed broken lines represent boundaries of the claimed medical device and form no part of the claimed design.

1 Claim, 8 Drawing Sheets
